[57] ABSTRACT

A novel nail file comprising an abrasive holding member and an abrasive paper characterized in that an elastic layer is interposed between said abrasive holding member and abrasive paper.

5 Claims, 6 Drawing Figures

PATENTED MAY 7 1974

3,809,101

FIG. 1A FIG. 1B FIG. 2A FIG. 2B

FIG. 3A FIG. 3B

NAIL FILE

BACKGROUND OF THE INVENTION

1. Field of the Invention

The present invention relates to a nail file or polisher.

2. Description of the Prior Art

Hitherto, a steel file or so-called "emery board" is used for abrading or polishing of the nail surface. The latter one is usually made of an elongated and thin strip of lauan or birch and an abrasive sheet such as emery cloth or paper directly applied on either or both sides of the strip. The nail abrasion or polishing is made by a reciprocal movement of the board in a compression contact with the nail surface. The abrading is effected by the frictional contact between the abrasive and nail surface during said reciprocal movement. In this case, the abrading and polishing effect is governed by the pull and push force against the friction because of the relatively rigid property of the strip material.

SUMMARY OF THE INVENTION

An object of the present invention is to provide a novel nail file or polisher having an effective nail abrasion or polishing.

The inventor found that an improvement in the abrading effect of a nail file of "emery board" type may be accomplished by the provision of an elastic layer between the abrasive holding member and the abrasive sheet. Specifically, the file of the subject invention comprises a knob or handle member and an elongated and thin abrasive holder connected thereto, the holder consisting of an abrasive holding member, an abrasive sheet of paper or cloth, and an elastic layer interposed between the holding member and the sheet.

BRIEF DESCRIPTION OF THE DRAWING

The other objects and advantages of the present invention may be fully understood by the following description in connection with the accompanying drawings; wherein

FIGS. 1-A and 1-B show a plan and side views respectively of one of the conventional "emery board";

FIGS. 2-A and 2-B are similar views of an embodiment of the present invention; and

FIGS. 3-A and 3-B show another embodiment of the present invention.

DESCRIPTION OF THE PREFERRED EMBODIMENTS

Referring to FIG. 1, one of the conventional nail files of "emery board" type 1 comprises an abrasive holding member 2 and an abrasive sheet 3. As shown in the figure, the abrasive sheet is directly applied to the holding member 2 of lauan or birch, and the abrading or polishing nail is performed by a reciprocal movement of the film on the nail surface in holding the file with two fingers.

One of the embodiments of the present invention as shown in FIG. 2 comprises a knob or handle member 4 and an abrasive holder connected thereto. The configuration and thickness of the whole file may be suitably selected for convenience of handling. As shown in the figure, the holder 5 is elongated and of relatively small thickness. The holder 5 comprises an abrasive holding member 7 of substantially uniform thickness

coextensive to the file. While the holding member 7 is shown as an integral part of the knob 4, it may be suitably connected to the latter by telescoping or threading in a connecting portion 6. The holding member may be preferably formed of a synthetic resin although it can be formed of lauan or birch. Most preferably, the holding member may be molded as an integral part with the knob using a synthetic resin.

It can be seen from FIG. 2-B that an embodiment of the present invention comprises an elastic layer 8 of a uniform thickness secured between the holding member 7 and the abrasive sheet 9. The physical properties of the elastic layer, such as strength and elasticity, may be suitably selected. Under investigation, the inventor found that the layer is most preferably made of urethane foam. The layer 8 usually has its thickness of 1-3 millimeters. The layer increases the polishing effect due to the restoring force derived from the shearing deformation of the layer caused by the pull-and-push force during the operation, and simultaneously affords a cushioning effect. In the present invention, an abrasive sheet 9 is secured on the layer with a suitable adhesive. The sheet 9 may be formed of a suitable paper or cloth having water resisting property, and abrasive powder is applied thereon with an adhesive by, e.g. a spraying process. The abrasive powder may be alumium, carborundum, garnet, diamond or synthetic abrasives.

When the upper surface of the member 7 is formed with a series of transverse recesses, an exchange operation of the abrasive sheet, together with the elastic layer, is feasible. Also, when the upper surface of the holding element 7 is recessed except for its peripheral portion 10, and the elastic layer is rigidly inlaid in the recess, peeling off the layer during the polishing operation may be avoided.

Another embodiment of the present invention is shown in FIG. 3. In this embodiment, the abrasive holding member is tapered on both its sides toward the tip of the file. Two elastic layers of uniform thickness are secured on the sides, and the abrasive sheets are applied thereon. Since the assembled holding member, elastic layer, and abrasive sheet are so designed that the width of the file is reduced gradually toward the tip of the file, this construction affords a smooth bending of the entire file structure. For convenience, one side of the file is provided with coarse abrasive for quick removal of nail surface, and the other side is provided with fine abrasive which will give a smooth finishing of the nail surface.

As mentioned as above, the provision of the elastic layer offers an excellent polishing effect due to the fact that the restoring force generated in the elastic layer in the frictional movement against the shearing deformation adds to the pull-and-push force applied during the reciprocal movement.

The entire dimension may be selected as desired so that the file of the present invention may be carried in a hand-bag.

What is claimed is:

1. In a nail file comprising an abrasive holding member having a handle portion and an abrasive sheet, the improvement comprising an elastic cushioning layer secured between said abrasive holding member and said abrasive sheet.

2. A nail file as defined in claim 1, wherein said abrasive holding member is reduced in its width and thickness toward the tip of said file.

3. A nail file as defined in claim 1 comprising two pairs of said elastic cushioning layer and said abrasive sheet, one pair positioned on each side of said holding member.

4. A nail file as claimed in claim 1, wherein said elastic cushioning layer comprises a layer of urethane foam.

5. A nail file as claimed in claim 1, wherein said elastic cushioning layer is elastically deformable under the shear forces occurring during use of said file.

[57] ABSTRACT

A novel nail file comprising an abrasive holding member and an abrasive paper characterized in that an elastic layer is interposed between said abrasive holding member and abrasive paper.

**REEXAMINATION CERTIFICATE
ISSUED UNDER 35 U.S.C. 307**

THE PATENT IS HEREBY AMENDED AS
INDICATED BELOW.

Matter enclosed in heavy brackets [ ] appeared in the patent, but has been deleted and is no longer a part of the patent; matter printed in italics indicates additions made to the patent.

AS A RESULT OF REEXAMINATION, IT HAS
BEEN DETERMINED THAT:

Claim 1 is determined to be patentable as amended.

Claims 2-5, dependent on an amended claim, are determined to be patentable.

New claims 6-28 are added and determined to be patentable.

1. In a nail file comprising an abrasive holding member having a handle portion and an abrasive sheet, the improvement comprising an elastic cushioning layer secured between said abrasive holding member and said abrasive sheet, *said abrasive holding member being stiff and comprising a relatively thin holding layer to which said elastic cushioning layer is secured, said holding member forming a stiff structure which can be manually held to cause a push-pull force during operation of the nail file, said elastic cushioning layer providing an improved polishing effect due to the restoring force derived from the shearing deformation of the elastic layer caused by the push-pull force provided by combined effect of the stiff backing layer, the elastic cushioning layer and the abrasive sheet when the abrasive sheet is drawn against the surface of the fingernail of the user.*

6. A nail file as claimed in claim 1, wherein said holding member is of substantially uniform thickness.

7. A nail file as claimed in claim 1, wherein said holding member is coextensive with said abrasive sheet and said elastic cushioning layer.

45

8. A nail file as claimed in claim 6, wherein said holding member is coextensive with said abrasive sheet and said elastic cushioning layer.

9. A nail file as claimed in claim 2, wherein said holding member is of substantially uniform thickness.

10. A nail file as claimed in claim 2, wherein said holding member is coextensive with said abrasive sheet and said elastic cushioning layer.

11. A nail file as claimed in claim 1, wherein said holding member comprises synthetic resin.

12. A nail file as claimed in claim 2, wherein said holding member comprises synthetic resin.

13. A nail file as claimed in claim 6, wherein said holding member comprises synthetic resin.

14. A nail file as claimed in claim 7, wherein said holding member comprises synthetic resin.

15. A nail file as claimed in claim 9, wherein said holding member comprises synthetic resin.

16. A nail file as claimed in claim 10, wherein said holding member comprises synthetic resin.

17. A nail file as claimed in claim 1, wherein said holding member comprises lauan.

18. A nail file as claimed in claim 2, wherein said holding member comprises lauan.

19. A nail file as claimed in claim 6, wherein said holding member comprises lauan.

20. A nail file as claimed in claim 7, wherein said holding member comprises lauan.

21. A nail file as claimed in claim 9, wherein said holding member comprises lauan.

22. A nail file as claimed in claim 10, wherein said holding member comprises lauan.

23. A nail file as claimed in claim 1, wherein said holding member comprises birch.

24. A nail file as claimed in claim 2, wherein said holding member comprises birch.

25. A nail file as claimed in claim 6, wherein said holding member comprises birch.

26. A nail file as claimed in claim 7, wherein said holding member comprises birch.

27. A nail file as claimed in claim 9, wherein said holding member comprises birch.

28. A nail file as claimed in claim 10, wherein said holding member comprises birch.
